(57) **CLAIM**

The ornamental design for a shoe, as shown and described.

DESCRIPTION

FIG. 1 is a lateral side perspective view of an embodiment of a shoe.

FIG. 2 is a medial side perspective view of the shoe of FIG. 1.

FIG. 3 is a medial side view of the shoe of FIG. 1.

FIG. 4 is a lateral side view of the shoe of FIG. 1.

FIG. 5 is a front view of the shoe of FIG. 1.

FIG. 6 is a rear view of the shoe of FIG. 1; and,

FIG. 7 is a partially enlarged view of a lateral side of a midsole of the shoe in FIG. 4.

The dash-dot broken line portions of FIGS. 1-6 are included to show the boundaries between the claimed and unclaimed portions only and form no part of the claimed design.

The stippled surface shading in FIG. 7 is included to show three-dimensional contours only and is omitted from FIGS. 1-6 for ease of illustration.

The remainder of the shoe shown in broken lines in FIGS. 1-6 shows unclaimed subject matter only and forms no part of the claimed design.
